ULTRASONIC GENERATOR

Robert H. Whittaker, Franklin Township, Westmoreland County, and John H. Thompson, Penn Hills, Pa., assignors to Westinghouse Electric Corporation, East Pittsburgh, Pa., a corporation of Pennsylvania

Filed Apr. 25, 1962, Ser. No. 190,113
8 Claims. (Cl. 116—137)

The present invention relates to a mechanical resonator and, more specifically, to a mechanical resonator which is resonant at a plurality of frequencies.

Mechanical type resonators or vibrator elements are utilized to generate air compression waves or control the devices remotely. These are commonly used to control television sets, opening and closing garage doors and could be used in various other remote control applications. In patent application, Serial No. 170,157, filed January 31, 1962, in the name of Arthur Nelkin, Robert A. Lester, Robert H. Whittaker and John H. Thompson there is disclosed a new and improved mechanical resonator or vibrator. The resonator disclosed therein operates in a flexural mode with a plurality of nodal diameters and it has been discovered that this resonator produces relatively high Q's with a relatively low loss to the mounting means of the resonator. The embodiment of the invention disclosed in the above cited patent application is actuated by imparting energy to the surface of the resonator preferably at the outer peripheral edge to provide the ultrasonic signals desired. The embodiment illustrated in the above-mentioned application is specifically illustrated as a disc, but could be a cylinder or plate or other configuration.

In previous ultrasonic remote control systems, the transmitter generally provides two signals of two predetermined frequencies so that the receiver can operate or be responsive to these two discrete signals. Some remote transmitters also utilized for discrete signals have four separate ultrasonic frequencies. For each ultrasonic signal in these transmitters, it was necessary to utilize a separate resonator for each ultrasonic frequency so that the receiver may be responsive to the two separate ultrasonic frequencies.

Accordingly, it is an object of the invention to provide a new and improved mechanical resonator which is resonant at a plurality of predetermined frequencies.

A further object of the invention is the provision of a new and improved ultrasonic generator utilizing a single flexural mode vibrator for generating two ultrasonic signals having two distinct predetermined frequencies.

It is a further object of the invention to provide a flexural mode resonator which can produce at least two ultrasonic signals having different predetermined frequencies and having relatively large amplitude and duration.

A mechanical resonator embodying the present invention includes a flexural mode vibrator having a plurality of nodal lines and more specifically intersecting nodal lines. The vibrator includes a mounting means which is connected to the vibrating element so that a minimum of energy will be dissipated from the vibrator through the connection of the mounting means to an external base or housing. In addition, the resonator has at least

2

one dissymmetry portion. This results in the vibrator having two resonant frequencies so that when energy is imparted to one predetermined area in the vibrator a signal having a first frequency will be generated by the vibrator whereas when energy is imparted to the vibrator at another predetermined area a second signal will be generated having a second predetermined frequency. Further, if energy is imparted to the vibrator at still other predetermined portions between the first and second predetermined areas the generator will produce a signal of the first predetermined frequency and the second predetermined frequency.

These and other advantages of this invention will be more clearly understood from the following description when taken in conjunction with the accompanying drawing, in which:

FIGURE 1 is an isometric view of an embodiment of the invention;

FIG. 2 is an elevation view of the generator illustrated in FIG. 1;

FIG. 3 is a side elevation view of the generator illustrated in FIG. 2;

FIG. 5 illustrates nodal diameters and planes of actuation of the generator shown in FIGS. 1 to 4;

FIG. 6 is another plan view illustrating nodal diameters of the generator illustrated in FIG. 2;

FIG. 7 illustrates nodal diameters and planes of actuation of the generator illustrated in FIGS. 1 to 4;

FIG. 8 is another plan view illustrating nodal diameters of the generator illustrated in FIG. 2;

FIG. 9 illustrates nodal diameters and planes of actuation of the generator illustrated in FIGS. 1 to 4;

FIG. 10 is an isometric view of another embodiment of the invention; and

FIG. 11 is an isometric view of still another embodiment of the invention.

In the above-mentioned patent application, Serial No. 170,157, filed January 31, 1962, in the name of Arthur Nelkin, Robert A. Lester, Robert H. Whittaker and John H. Thompson, there is disclosed an ultrasonic generator for producing ultrasonic signals. This generator utilizes a flexural mode vibrator, having a plurality of nodal diameters, to produce by the vibrations thereof ultrasonic signals. In this flexural mode vibrator, the mounting means is a pin which is located at a point on the surface of the vibrator so that equal and opposite vibratory forces are applied to this pin so as to provide an undamped connection between the vibrating disc in the mounting pin. Being located in the center of or concentric with one of the circular surfaces, the vibratory forces projected on the pin are equal and opposite, and since the pin is integral with the vibrator the forces are applied to the pin without any damping so that the forces reaching the pin will not be unbalanced. As such the free end of the mounting means or pin can be mounted by any conventional connection without losses of energy through the mounting means, since energy imparted to the disc is retained in the disc due to the cancellation afforded by the concentric mounting and the undamped connection with the resonator.

In the present invention, as shown in FIGS. 1 and 3, a generally similar vibrating plate or member 10 is utilized.

The embodiment illustrated therein comprises a vibrator 10 comprising a circular plate or cylinder 11 having an upper circular planar surface 12 and a lower planar surface 13 which is circular and parallel to the upper circular planar surface 12. Extending between the upper and lower surfaces 12 and 13 is the cylindrical side surface 14 which is normal to surfaces 12 and 13. A circular mounting pin 16 extends downwardly from and is concentric with the lower surface 13. The mounting pin 16 is integral with the disc 11 so that the flexural mode vibrating forces from disc 11 are applied to the pin 16, are undamped and are equal and opposite. By having the pin 16 as the integral undamped connection with the surface 13, the energy applied to the pin 16 prevents the energy from passing out through the mounting threads 17 of the pin 16. This enables the relatively large amount of the energy imparted to the disc to be converted to ultrasonic signals since no energy loss occurs empty at the mounting threads 17 or any other connection at the free end of pin 16. This mounting is the same as that described in the above patent application. For illustration purposes, as shown in FIG. 1 and FIG. 3, there is disclosed a mounting base 20, having a threaded aperture 21 for receiving the thread 17 of the mounting pin 16. The upper surface of the base 20 is based a distance S1 from the lower surface 13 from the disc 11. If the upper surface of the base 20 is of any appreciable size compared to surface 13, and is relatively close to the lower surface 13 optimum performance will be realized when this distance is equal to an odd quarter wavelength or any multiplier thereof of the frequency of vibration of the disc. More specifically, the distance in free air S1 should not, for optimum performance, be an even quarter wavelength of the frequency of the vibration of the disc since this would tend to cancel and provide a loss of energy transmitted by the vibrations.

In the above-mentioned patent application, the resonator described therein was actuated by striking the disc to thereby set the disc into vibration in the flexural mode with two nodal diameters which are located at 45° from the point at which the disc was struck. This produced an ultrasonic signal in the range of 10 to 100 kilocycles at a predetermined frequency. In the embodiment of the present invention illustrated in the drawing, one or more holes are drilled inwardly to form a geometrical and mass dissymmetry in the cylinder. In so doing, the flexural mode disc is capable of producing two signals at two different frequencies depending upon where the disc is struck. If more than one hole is drilled in the side surface 14, it should be located at 90° from the other holes. The embodiment illustrated in FIG. 1 employs four radially disposed holes located at 90° from each other on the surface of the cylindrical side surface 14. These holes are illustrated by numeral 15 as shown in FIG. 1.

In the embodiment shown in FIG. 1, an actuating means 40 includes three separate actuating members 41, 43 and 45 having metallic striker elements 42, 44 and 46 mounted theron. The actuating members 41, 43 and 45 are leaf springs and preferably have a spring constant so that with the metallic striker elements 42, 44 and 46 being positioned a predetermined distance from the side surface 14 so that when the springs 41, 43 and 45 are moved a predetermined distance away from disc 11 they will impart a single actuating blow to the disc to set the disc into vibration. If the disc is actuated by the striker element 42, the disc or plate 11 will be set into a flexural mode vibration having two nodal diameters d_1 and d_2 as shown in FIG. 1 and FIG. 5. The ultrasonic signal effected thereby will have a single frequency predetermined by the dimensions of the device. In order to actuate the disc 11 into vibration having nodal diameters d_1 and d_2 , the energy can be imparted to the disc or the disc can be struck, virtually at any point wherein the planes P1 and P2, as shown in FIG. 5, cross the disc 11. This is illustrated in FIG. 5 by the actuating areas R1 and R2. If

only one hole is drilled, these areas of energization R1 and R2 remain the same and so long as energy is imparted in or on these rectangles, to the disc 11, the frequency of the signal generator thereby will be a predetermined frequency depending upon the depth and the number of holes 15. The disc 11 should be struck near the peripheral surfaces 14 to provide maximum output. The plane P1 is a plane which passes normal to the surfaces 12 and 13 of the disc and intersect or pass through the center of the holes 15. These planes are located at 90° from each other as are the rectangular areas R1 and R2. The nodal diameters d_1 and d_2 pass through the center of the peripheral surfaces 14 midway between and parallel to the planar surfaces 12 and 13, and intersect in the center of the disc. As shown in FIG. 5 and FIG. 6, the nodal diameters d_1 and d_2 are located at 90° to the planes P1 and P2.

If it is desired to actuate another signal having a different frequency than the signal described in the above paragraph, energy is imparted to the disc by way of the spring leaf 43 and the striker element 46 striking the disc preferably by a single blow to impart energy thereto. When the disc 11 is actuated by the striker element 46, another signal is produced by the disc having a lower frequency than the previously described signal. The vibrations resulting from the striker 46 have nodal diameters d_3 and d_4 which are midway between and parallel to the planar surfaces 12 and 13. The nodal diameters d_3 and d_4 are located in the same plane and are positioned at 90° with each other. As shown in FIG. 7, these nodal diameters pass through the center of the apertures or holes 15 which are also located midway between and parallel to the planar surfaces 12 and 13. As shown in FIG. 8, the leaf spring 43 and the striker 46 are positioned so that the striker 46 contacts the disc at a point which is located in a plane P3. The planes P3 and P4, as shown in FIG. 7, form actuating areas R3 and R4 at the intersection of disc 11. The planes P3 and P4 are normal to the surfaces 12 and 13 so as to form rectangular actuating areas R3 and R4. The planes P3 and P4 are located at 90° to each other and intersect at the axis of the disc. Planes P3 and P4 are located at 45° to planes P1 and P2. When energy is imparted to the disc in actuating areas R3 and R4, vibrations will be set up with a flexural mode with two nodal diameters d_3 and d_4 . Although the embodiment in the drawing illustrates four holes or portions of dissymmetry, only one hole need be drilled to produce two different frequencies by the same disc. As shown in FIG. 7 and FIG. 8, the striker element strikes the disc at a point on the rectangular area R3 and hence sets up vibrations with the nodal diameters d_3 and d_4 . If the energy is applied near the center of the disc adjacent the intersection of R3 and R4, very little energy will be imparted in the form of vibrations to the disc. For optimum efficiency and performance, the disc should be actuated in the outer edges of the rectangular areas R3 and R4 near surfaces 14. This is likewise true of the actuating areas R1 and R2. By setting the disc 11 into vibration by imparting energy to the actuating areas R3 and R4, the flexural mode vibration set up will have a frequency substantially lower than the frequency of the vibration set up by actuating the disc in actuating areas R1 and R2.

Hence, it is seen that, by drilling inwardly extending holes from the peripheral edge surfaces 14, toward the axis of disc 11, a single disc or vibrator can be employed to transmit two ultrasonic signals. As shown in FIG. 1, the striker element 46 actuates the disc 11 by striking element on the area R3. The same signal could be produced by actuating the disc by striking the element in the area R4. The area R3 is located at 45° to the area R1 and the plane P1. If it is desired to produce a signal having two discrete frequencies, that is, the frequency produced by striker 46 and the frequency produced by striker 42, the actuating member with leaf spring 43 and actuating striker element 44 are employed to strike the disc.

As shown in FIG. 9, to produce a signal having both frequencies of substantially equal magnitude, such as by striker element 44, the disc is actuated by applying energy to the actuating areas R5 and R6. Actuating areas R5 and R6 are described by the intersection planes P5 and P6 with disc 11, respectively, which are located at 90° to each other and are normal to the surfaces 12 and 13. The plane P5 is located midway between planes P1 and P3 that is, it is 22½° from planes P1 and P3. P6 which forms actuating area R6 is located at 90° to and normal to plane P5 and is midway between planes P2 and P4. That is, it forms a 22½° angle with planes P2 and P4. By actuating the disc in actuating areas R5 and R6, two signals will be produced one having the frequency of a signal that would be produced by actuating the disc in actuating areas R1 and R2 and the other signal having the frequency of actuating the disc in actuating areas R3 and R4. These signals will be of relatively equal amplitude and ringing time. If the disc is actuated between actuating area R5 and actuating area R3, there will be two separate signals produced, however, the signal having the lower frequency, that is, the signal actuated by imparting energy to actuating area R3, will have a greater amplitude and about the same ringing time than the other signal of the higher frequency. This is likewise true if the disc is actuated between actuating area R6 and actuating area R4. If, however, the disc is actuated between actuating area R5 and actuating area R1, so that for example the striker element 44 is positioned closer to striker element 42 than to striker element 46, there will be two frequencies produced, however, the higher frequency will have a greater amplitude and about the same ringing time.

In drilling the disc radially with a single hole 15 or four quadrant holes as described above, double mode operation is obtained so that two signals, one having a frequency f_1 is below the undrilled disc frequency f_0 and the other signal has a frequency f_2 which is above the undrilled frequency f_0 . Increasing the hole depth increases the separation of f_1 and f_2 as shown in the tables below. When the disc is drilled through the surfaces 12 or 13 actually off-center of the disc axis, as by a hole 19, the two frequencies f_1 and f_2 are both below f_0 and their separation increases with the hole depth, hole diameter and number of holes. If only one hole 19 is drilled off-center in disc 11 the Q of the device will be lowered. If a similar hole is positioned an equal distance from the center and on the same diameter the Q will not be changed.

If a hole 18 is drilled actually through the surface 12, as shown in FIG. 11, of the disc having no radial hole, the frequency of f_0 is reduced. If there are radial holes 15 in the disc 11, as shown in FIG. 11, this hole 18 reduces f_1 and f_2 equally. When the hole 18 is drilled in a disc having the radial holes or hole 15, although the frequencies f_1 and f_2 are lower, the separation or beat frequency between frequencies f_1 and f_2 remains constant when this operation is carried out. When hole 19 is drilled off the axis of the disc, the separation afforded thereby between frequencies f_1 and f_2 increases with the hole depth as shown in the following tables.

A relatively high Q material should be used to construct the discs (at least 5,000-10,000) to provide a usable output. The mass dissymmetry of disc 11 formed by holes 15 and 19 can be accomplished by grooves, filing the surfaces, some discontinuity of mass or material other means in the disc 11 to produce two signals from the same vibrator. If only one dissymmetry of mass portion is formed, the Q of the system will be lowered somewhat. If a second dissymmetry portion is formed it increases the frequency separation. This second dissymmetry portion should be similarly formed on the diametrically opposite side of the disc axis or at 90° to the first portion (and equally spaced therefrom) in order to enable production of two separate frequencies. If this second portion is not similar and equally spaced from

the disc axis, and at 90° or 180° from the first dissymmetry portion there will be coupling between the two frequencies or two modes and any signal produced by the disc will have portions of both frequencies.

5 The following are samples of flexural discs constructed that produced two signals having two separate frequencies. All these discs had a Q of at least 20,000 with the distance S1 being approximately one quarter wavelength of the undrilled resonant frequency of the disc.

10 Flexural disc with single radial hole (f_0 =frequency of undrilled disc; f_1 and f_2 being the two frequencies caused by the dissymmetry of mass):

Disc material=7075S-T6 aluminum

Disc diameter=1.500 inches

All the above vibrators had a Q of at least 20,000 when tested in free air without a housing. Other samples were tested having Q's of at least 20,000 where the dissymmetry of mass of the disc was caused by a flaw in the material, by filing a portion of the disc etc., to thereby produce two separate frequencies from the disc. It will be noted that these frequencies are not overtones.

Although this invention has been described in connection with this specific embodiment, it will be apparent to those skilled in the art that changes and arrangements in parts can be made to suit the requirement without departing from the spirit and scope of the invention.

We claim as our invention:

1. A mechanical resonator comprising, a vibrator resonant in a flexural mode having a plurality of nodal lines, said vibrator having a first surface and a second surface opposite said first surface, mounting means supporting said vibrator, said vibrator having a dissymmetry portion and means to actuate said vibrator into vibration in a flexural mode with a plurality of nodal lines.

2. A mechanical resonator comprising, a vibrator resonant in a flexural mode having a plurality of intersecting nodal lines, said vibrator having a first surface, and a second surface opposite said first surface, mounting means for supporting said vibrator centrally of said first surface, said vibrator having a dissymmetry portion and means to actuate said vibrator into vibration in a flexural mode with a plurality of intersecting nodal lines.

3. A mechanical resonator comprising, a vibrator resonant in a flexural mode having a plurality of nodal lines, said vibrator having a first surface, and a second surface opposite said first surface, mounting means supporting said vibrator centrally of said first surface, an aperture extending inwardly from the surface of said vibrator, and means to actuate said vibrator into vibration in a flexural mode with a plurality of nodal lines.

4. A mechanical resonator comprising, a vibrator resonant in a flexural mode having a plurality of intersecting nodal lines, said vibrator having a first surface, and a second surface opposite said first surface, mounting means supporting said vibrator, a dissymmetry portion on the surface of said vibrator, and means to actuate said vibrator into vibration in a flexural mode with a plurality of intersecting nodal lines.

5. A mechanical resonator comprising, a vibrator resonant in a flexural mode having a plurality of intersecting nodal lines, said vibrator having a first surface and a second surface opposite said first surface, an axis normal to said first surface and passing through the intersection of said nodal lines, mounting means supporting said vibrator centrally of said first surface, said vibrator having a dissymmetry portion, means for applying energy to said vibrator at a predetermined reference point to actuate said vibrator into vibration in a flexural mode with a plurality of nodal lines, the plane defined by said predetermined reference point and said axis and a plane defined by the said dissymmetry portion and said axis being at an angle of N times forty-five degrees where N equals any odd integer.

6. A mechanical resonator comprising, a vibrator resonant in a flexural mode having a plurality of nodal diameters, said vibrator having a pair of parallel circular planar surfaces with peripheral edge surfaces extending therebetween a pin extending outwardly from and concentric with one of said planar surfaces, said pin being integral with said vibrator, a hole extending inwardly from said peripheral side surfaces toward the axis of said vibrator, means for applying mechanical energy to said vibrator at a predetermined point on the surface thereof to actuate said vibrator into vibration in a flexural mode with a plurality of nodal diameters, said predetermined point and said axis defining a plane positioned at an angle of N times forty-five degrees with a second plane defined by the center of said hole and said axis where N equals any odd integer and means for applying energy to said vibrator in said second plane to actuate said vibrator into vibration.

7. A transmitter for generating ultrasonic signals at a plurality of predetermined frequencies, comprising, a cylindrical vibrator resonant in a flexural mode having a plurality of nodal diameters, said vibrator having a first planar surface and a second planar surface opposite and parallel to said first planar surface, cylindrical side surfaces extending between said first and said second surfaces, a mounting pin, connecting means providing an undamped connection between the center of said first surface and said mounting pin, a plurality of holes extending inwardly from said side surfaces toward the axis of said cylindrical vibrator, said holes being spaced at an angle of approximately ninety degrees relative to said axis, means for applying mechanical energy to said vibrator and a predetermined reference point on the surface of said vibrator to actuate said vibrator into vibration, said predetermined point and said axis defining a plane which is located at a forty-five degree angle with a plane defined

by the center of one of said holes and said axis, and means for applying energy to said vibrator on the surface thereof at another reference point, said other reference point being located in a plane defined by the center of one said holes and said axis.

8. A transmitter for generating ultrasonic signals at predetermined frequencies comprising, a vibrator resonant in a flexural mode having a plurality of intersecting nodal lines, said vibrator having a first surface and a second surface opposite said first surface, side surfaces between said first and second surfaces, mounting means, connecting means for providing an undamped connection between said mounting means in the center of said first surface, a hole extending inwardly from said side surface, means for applying energy to said vibrator at a predetermined reference point on the surface therefor to actuate said vibrator into vibration in a flexural mode with a plurality of intersecting nodal lines, said reference point located in a plane including the axis of said vibrator which defines

10 an angle with a plane defined by the axis of said vibrator in the center of said hole equal to $n \times 45^\circ + 22.5^\circ$ where n equals any integer or zero.
